UNITED STATES PATENT OFFICE

JAMES L. ARTHUR, OF ANDERSON, INDIANA, ASSIGNOR TO DELCO-REMY CORPORATION, OF ANDERSON, INDIANA, A CORPORATION OF DELAWARE

IGNITION DEVICE

Application filed March 15, 1929. Serial No. 347,277.

This invention relates to improvements in ignition devices for internal combustion engines.

It has been found that an engine when comparatively cold will start more readily if the time of sparking impulse has been advanced beyond the normal high degree. After the engine has become self operative, however, and the temperature thereof has risen, it is of course necessary for efficient engine operation to again readjust the timing of the sparking impulses so that they will fall within the proper range of normal engine operation.

It is among the objects of the present invention to provide means for automatically adjusting the ignition timer in accordance with engine temperatures so that the time of sparking impulses will be substantially advanced when the engine temperature is comparatively low.

Further objects and advantages of the present invention will be apparent from the following description, reference being had to the accompanying drawings, wherein a preferred form of the embodiment of the present invention is clearly shown.

In the drawings:

Fig. 1 illustrates the ignition device applied to the crank case of an engine.

Fig. 2 is a part sectional view taken along the line 2—2 of Fig. 1.

Fig. 3 is a plan view of the ignition device with the distributor cap removed.

Fig. 4 is a detail sectional view taken along the line 4—4 of Fig. 2.

The timer designated as a whole by the numeral 20, comprises a housing 21 having a tubular extension, one portion thereof designated by the numeral 37 being of greater transverse dimensions than the portion 22, the latter portion fitting into a recess provided in the crank case 23 of the engine whereby the ignition unit or timer 20 is supported on said crank case. The tubular extension provides a bearing for the drive shaft 24 of the ignition unit which supports a pinion 25 in driving engagement with the pinion 26, the latter pinion being driven by the engine. The timer housing 21 is cup-shaped and contains the circuit interrupter whose operation

provides for the sparking impulses of the engine.

The circuit interrupter provides two contacts, a movable one designated by the numeral 27, and a stationary one designated by the numeral 28. The movable contact 27 is carried on the free end of contact lever 29 pivoted on pin 30 which is supported in the timer housing 21. Contact arm 29 has a rubbing block 31. A cam 32 is carried by the end of the drive shaft 24 extending into the housing 21. Rubbing block 31 is urged into engagement with cam 32 by a spring 33, one end of which is electrically connected with the terminal screw 34 insulated from the timer housing 21 in any suitable manner. When the rubbing block 31 is off the lobes of the cam 32, contact 27 will engage the stationary contact 28 which is carried by a bracket 35 adjustably supported within the housing 21.

Cam 32 rotates in a direction of the arrow 36. In order to advance the time of sparking impulses the housing 21 may be rotated in a direction opposite to the rotation of cam 32 whereby the instant of contact separation is advanced. Rotating the housing 21 in the direction in which the cam is rotating will retard the time of circuit breaking, or more specifically will cause the contacts 27 and 28 to be opened at a later moment.

As shown in Figs. 1, 2 and 4, the portion 37 of the timer has an arm 40 secured thereto, said arm having a split hub portion which is clamped on to the portion 37 of the timer by the screw 42 and its associate nut 43. Thus rotation of lever 40 will tend to rotate the housing portion 22 in its bearing provided by the crank case 23 so that said housing is rotated relative to the drive shaft 24 which carries the cam 32.

The means for manually adjusting the timer 20 comprises a rod 50, one end of which is secured to the spark adjusting lever carried by the steering wheel and not shown on the present drawings, the other end of said rod being secured to a lever 41 by the pin 51. The lever 41 has a hub portion rotatably supported on the portion 37 of the housing 21. Adjacent one end of the lever 41 there is pro-

vided a slot 44 through which extends the screw-threaded shank portion of the screw 45 forming a part of a drag element which prevents accidental movement of the lever 41. 5 The screw 45 of the drag element has an enlarged shank portion 46 and a head portion 47 of larger transverse dimensions than the shank 46. A cup 48 having an opening in its bottom wall through which screw 45 extends, is urged into gripping engagement with the lever 41 by a spring 49 interposed between the cup 48 and the head 47 of the screw 45. 10 The arm 40 is connected with the lever 41 by a thermostatic link adapted to automatically adjust the ignition timer relative to the manually operated lever 41. This link connection comprises a cup-shaped housing 60 having an extended portion 61 pivotally secured to the arm 40 by pin 62. The open end of the cup-shaped housing 60 is provided with a cover 63 having a central lug portion 64 apertured slidably to support the stem 65, the inner end of which extends into housing 30 having a plate 66 attached thereto. The outer end of stem 65 is attached to the lever 41 by a pin 67. Between plate 66 and the cover 63 of the housing, there is provided a spring 68 urging the housing 60 toward the lever 41. Between the plate 66 and the inner end surface of the housing 60 are provided the thermostatic elements which automatically adjust the timer in response to varying engine temperatures. 15 A plurality of plates or washers 69 are provided in the space between the plate 66 and the bottom of the housing 60, each washer being engaged on each side thereof by the peripheral edge of a dished bi-metallic thermostatic element. Fig. 2 clearly shows these bi-metallic discs, the edges of which are slidably supported on washer 69, one bi-metallic disc having its peripheral edge slidably engaging one surface of the plate 66. At normal engine temperatures the discs 70 will assume a shape whereby the linkage connection between the lever 41 and arm 40 will be such that the timer will be in its proper advance position when the spark control lever, 20 not shown but secured to the rod 50, is in its fully advanced position. Decreasing temperatures tend to contract the discs 70 whereby they will be more arcuated, that is, more deeply dished, and thus the arm 40 will be automatically moved away from the lever 41, thus the housing 21 will be rotated clockwise, or in a direction opposite the rotation of cam 32 and consequently at these lowering temperatures the timer 21 will be adjusted to advance the time of sparking impulses beyond a normal advanced position. Increasing temperatures of the engine will cause the discs 70 to expand, resulting in their becoming more flat or dished less deeply, and thus 25 spring 68 may function to move the housing

60 toward the lever 41, resulting in a counterclockwise movement of the housing 21, or in a direction of the arrow 36 which is the retarding direction for the spark timer, and thus the timer will again be moved to properly adjust the time of sparking impulses for the normal operation of the engine. 70

From the foregoing it may be seen that without adjusting the manual lever 41, the linkage connection including the thermostatic disc 70 and spring 68 contained within the housing 60 will automatically adjust the timer relative to the manually operable lever 41 in accordance with engine temperature conditions so that if the engine is cold, the time of sparkling impulses will be properly advanced and after the engine has become self operative and warmed up, the thermostat will automatically adjust the timer to the position in which the normal time of sparking impulses is again restored to normal. 80

While the form of embodiment of the present invention as herein disclosed, constitutes a preferred form, it is to be understood that other forms might be adopted, all coming 90 within the scope of the claims which follow.

What is claimed is as follows:

1. An ignition device for an internal combustion engine comprising, in combination a timer; manually operable means for adjusting the timer to vary the time of sparking impulses; and temperature controlled means for adjusting the timer relative to the manually operable means in response to varying engine temperatures. 100

2. An ignition device for an internal combustion engine comprising, in combination, a timer; means for adjusting the timer to vary the time of sparking impulses; a manually operable lever; and temperature controlled means connecting the said lever with the timer adjusting means. 105

3. An ignition device for an internal combustion engine comprising, in combination, a timer; means for adjusting the timer to vary the time of sparking impulses; a lever; and a link connecting said means and lever, said link being expansible and contractable with increasing and decreasing temperatures respectively. 110

4. An ignition device for an internal combustion engine comprising, in combination; a timer including a casing, a circuit interrupter in said casing and a cam for operating the interrupter; a lever attached to the casing; a lever rotatably supported by the casing; and a link connecting said two levers, said link varying in length in response to varying engine temperatures. 120

5. An ignition device for an internal combustion engine comprising, in combination, a timer; a manually operable lever; linkage connecting the lever with the timer said linkage including a thermostatic element ex- 130

pansible and contractable in accordance with varying engine temperatures.

5 6. An ignition device for an internal combustion engine comprising, in combination, a timer; an arm on the timer for adjusting it to vary the time of sparking impulses; a lever rotatably supported on said timer; and a thermostatic element connecting the lever to the arm.

10 7. An ignition device for an internal combustion engine comprising, in combination, a timer; an arm for adjusting the timer to vary the time of sparking impulses; a manually operable lever; a cylinder attached to the arm; a piston in the cylinder, attached to the lever; and thermostatic means within the cylinder for moving the piston in said cylinder.

15 8. An ignition device for an internal combustion engine comprising, in combination, a timer; an arm for adjusting the timer to vary the time of sparking impulses; a manually operable lever; a cylinder attached to the arm; a piston in the cylinder, attached to the lever; thermostatic means within the cylinder adapted to expand in response to rising engine temperatures and move the piston relative to the cylinder; and a spring urging the piston against the thermostatic means to move 20 said piston in the opposite direction when said thermostatic means contracts in response to lowering temperatures of the engine.

25 In testimony whereof I hereto affix my signature.
